UNITED STATES PATENT OFFICE.

LESLIE M. PARKER, OF EVANSTON, ILLINOIS.

DEMOUNTABLE STRUCTURE.

Application filed January 6, 1923. Serial No. 611,012.

To all whom it may concern:

Be it known that I, LESLIE M. PARKER, a citizen of the United States, residing at Evanston, in the county of Cook and State of Illinois, have invented a certain new and useful Improvement in Demountable Structures, of which the following is a specification.

This invention relates to demountable structures, the members from which they are made, and the process of making the structures and the members. It has for one object to provide a process whereby a large number of different types of structures may be built from standard parts and in which the number of types of such standard parts is reduced to the minimum. Another object is to provide a limited number of standard parts which may be assembled in varying combinations so as to produce a large variety of different structural forms. Another object is to provide a limited number of standard parts from which practically any structural form may be assembled and to provide such parts so that they may be used first in one combination and then in another. Other objects will appear from time to time throughout the specification and claims.

My invention is illustrated more or less diagrammatically in the accompanying drawings, wherein:

Figure 1 is a perspective view of a bridge;

Figure 2 is an elevation of three of the parts assembled to form a structural unit;

Figure 3 is a side elevation of one end of the parts shown in Figure 2;

Figure 4 is an enlarged side elevation indicating a union of such parts;

Figure 5 is a side elevation showing another part;

Figure 6 is a fragmentary side elevation of a built-up unit which may be formed of a plurality of unions shown in Figure 2;

Figure 7 is a partial perspective view similar to Figure 1 showing a modified form, with an additional joining plate in use;

Figure 8 is a detailed elevation on an enlarged scale showing such plate;

Figure 9 is a perspective of the plate.

Like parts are designated by like characters throughout.

A is a longitudinal structural member which is here shown as being made of wood but which may be made of any material. Adjacent each of its ends a nail or pin A¹ is positioned in the member A.

B is a union member here shown as being composed of metal, although it might be of any other suitable material. It is formed of the laterally extending web portion B¹ through which a perforation B² is formed. At its other end it carries the socket part B³ which has formed in it the bayonet lock B⁴. The member B is adapted to be slipped over one end of the member A and the pin A¹ is engaged in the bayonet lock B⁴.

To provide for lateral connections the member C is used. This member as here shown is formed substantially like the member B. It is provided with the web portion C¹, the perforation C² and the socket member C³ which has in it a bayonet lock similar to the lock shown at B⁴. As here shown the member C is formed from the member B by bending the web portion B at right angles to the socket portion B³.

D, D are bolts by means of which a number of unions are joined or secured together in a structure.

E is an attaching plate bent into two portions joining each other at an angle. It is intended for joining portions of the structure which lie in different planes. Each portion of the plate E is perforated as at E¹ E².

As shown in Figure 7 bracing in the top and bottom of the bridge is provided. Such bracing is effected by longitudinal bracing members F, F, each of which has attached to each of its ends a union member B which is identical with the union members shown in the other figures.

As shown in Figure 7 instead of using a bent union member such as that shown in

2

detail in Figure 5, all of the union members used in the structure are identical and cross connections and connections of portions of the structure lying in different planes are made by the use of an additional member. By this means cross bracing is possible without increasing the number of types of parts since there need be no additional lengths added to effect this bracing. In this 10 form the top and sides of a bridge might be identical. Thus the structure can be built with a smaller number of types of parts than would be the case where the bent union member is used.

15 Although I have shown an operative device, still it will be obvious that many changes in size, shape and arrangement of parts can be made without departing materially from the spirit of my invention, and 20 I wish therefore that my showing be taken as in a sense diagrammatic.

The use and operation of my invention are as follows:

When it is desired to form a structure the 25 necessary number of longitudinal members is assembled and one of the union fittings is positioned on each end of these. If the member is to be used for a longitudinal connection, the flat metal fittings are used, and 30 if it is used for lateral connections the bent metal fitting may be used. When the parts have been thus assembled, they are then used to form a structure of any suitable type. They may be assembled to form a 35 bridge or to form a truss or arch of any type necessary. The lateral connections as shown are offset from the point of connection of the members which are united to form a joint either by the use of the bent 40 union member or by the use of an additional angular attaching plate. This feature permits of rotation of the connection member, and this rotation is particularly shown in Figure 4. By means of this arrangement 45 the lateral connections may be manipulated about a point and in this fashion the level of any structure which is supported from them may be varied and slight variations may be made to counteract inaccuracies 50 which may have occurred elsewhere in the structure or which may be due to sagging or other unavoidable action.

As shown in Figures 7, 8, and 9 no bent 55 union members are used, and thus the structure there shown requires only two types of joining members, namely, the single flat union member and the single angular joining plate. The type of connection shown in 60 the structure of Figure 7 and illustrated in detail in Figure 8 permits of considerable rotation of the parts. For example, the plate E may be rotated throughout a complete circle with reference to the upward extension of the lower socket union member, and 65 the cross member may be rotated throughout

an entire circle with reference to the upper portion of the connecting plate E. These two rotations permit a variety of angular adjustments, not necessary in the structure shown in Figure 7 but available for structures of other types and proportions. They are therefore valuable.

I claim:

1. A construction member comprising an intermediate longitudinal element of relatively light, bulky material, and identical unit union members of a different material 75 removably secured to each end thereof.
2. A construction member comprising an intermediate longitudinal element of relatively light, bulky material, and identical metallic unit union members removably secured to each end thereof. 80
3. A construction member comprising an intermediate longitudinal element of wood, 85 and identical metallic unit union members removably secured to each end thereof.
4. A construction member comprising an intermediate longitudinal element of relatively light bulky material, a projecting pin 90 adjacent each end thereof, metallic union members removably secured to each end thereof, each of said member being provided with a slot adapted to engage and lock upon said pin. 95
5. In a composite structure, a plurality of removable unit members including longitudinal members and identical removable connecting members attached one to each end of each of said longitudinal members, 100 a plurality of said attaching members joined to form a composite union of said longitudinal members. 100
6. A composite structure formed of a plurality of removable members, each of said 105 members provided with a longitudinal portion and with identical removable unit attaching members at its end.
7. In a composite building structure, a plurality of removable members comprising longitudinal elements and identical removable connecting elements attached one to each end of each of said longitudinal elements, a plurality of said attaching elements 110 being joined in one plane to form a union 115 of said longitudinal members, and attaching plate secured thereto in said plane and having a portion lying in a plane at an angle to the first plane, and a plurality of attaching members lying in said different plane, 120 and joined to each other and to said union member.
8. The process of building structures which consists in assembling a plurality of longitudinal members, removably joining to 125 each end of each of said members an identical attaching member and joining a plurality of said attaching members to make a union between a plurality of said longitudinal members to form the structure. 130

9. A construction member comprising an intermediate longitudinal element and a pair of single unit union members removably secured thereto one at each end thereof.
10. A construction member comprising an intermediate longitudinal section and a pair of substantially identical unit union members removably attached one at each end

thereof, the said parts forming in combination a complete building element adapted to 10 be associated with other similar composite elements.

Signed at Chicago, county of Cook and State of Illinois, this 4th day of January, 1923.

LESLIE M. PARKER.
